(57) CLAIM

I claim the ornamental design for a watch case with engraved characters on flange, as shown and described.

DESCRIPTION

FIG. 1 is a front plan view of a design for the watch case with engraved characters on flange;

FIG. 2 is a bottom plan view of the claimed design;

FIG. 3 is a back plan view thereof;

FIG. 4 is a top plan view thereof;

FIG. 5 is a left side view thereof;

FIG. 6 is a right side view thereof;

FIG. 7 is a perspective view showing the front, bottom and right sides and a first portion of the flange of FIG. 1 thereof; and,

FIG. 8 is a perspective view showing the front, top and left sides; and a second portion of the flange of FIG. 1 thereof. The broken line disclosure in the drawings is for illustrative purposes only and forms no part of the claimed design.

The engraved flange comprises a repeating sequence of characters positioned to provide the appearance of minute indicators and a different character located at, and denoting, the “12 o’clock” position.
